(57) **CLAIM**

The ornamental design for a disposable electrocardio electrode, as shown and described.

DESCRIPTION

FIG. 1 is a front perspective view of the disposable electrocardio electrode showing the design;

FIG. 2 is a rear perspective view of the disposable electrocardio electrode showing the design;

FIG. 3 is a front elevational thereof;

FIG. 4 is a rear elevational view thereof;

FIG. 5 is a left side view thereof; and,

FIG. 6 is a right side view thereof.
